FIG. 1 is a front view of toilet assistive device for the physically handicapped showing my new design;

FIG. 2 is a back view thereof;

FIG. 3 is a side view thereof;

FIG. 4 is an opposite side view thereof;

FIG. 5 is a top view thereof;

FIG. 6 is a bottom view thereof;

FIG. 7 is a perspective view of the present invention; and,
FIG. 8 is another perspective view of the present invention in a condition of use.

In FIG. 8, the broken lines showing of environmental structure for purposes of illustrating the toilet assistive device for the physically handicapped in a condition of use. The broken lines and the structure they depict form no part of the claimed design.
